[57] CLAIM

The ornamental design for a game machine, as shown and described.

DESCRIPTION

FIG. 1 is a perspective view of a first embodiment of a game machine showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof.

FIG. 8 is another perspective view thereof, wherein the cover portion is in the open position.

FIG. 9 is a perspective view of a second embodiment of a game machine showing my new design;

FIG. 10 is a top plan view thereof;

FIG. 11 is a left side elevational view thereof;

FIG. 12 is a front elevational view thereof;

FIG. 13 is a bottom plan view thereof;

FIG. 14 is a right side elevational view thereof;

FIG. 15 is a rear elevational view thereof; and,

FIG. 16 is another perspective view thereof, wherein the cover portion is in the open position.
